SUPPORT STAND FOR A TELEVISION RECEIVER OR SIMILAR ARTICLE

Paul S. Bush, ½ Bush Brothers Products Corporation,
312 Fair Oak St., Little Valley, N.Y. 14755

Filed Jan. 28, 1974, Ser. No. 436,886

Term of patent 14 years

Int. Cl. D6—99

U.S. Cl. D6—27

Fig. 1

Fig. 2

Fig. 3

Fig. 4

Fig. 5

Fig. 6

FIG. 1 is a front elevational view of a support stand for a television receiver or similar article according to the new design.

FIG. 2 is a rear elevational view of the support stand for a television receiver or similar article of FIG. 1.

FIG. 3 is a view in side elevation of the support stand for a television receiver or similar article showing the new design and showing one form of side panel which may be used with the design.

FIG. 4 is a plan view of the support stand for a television receiver or similar article showing the design of FIG. 1.

FIG. 5 is a view in side elevation of the support stand for a television receiver or similar article similar to that shown in FIG. 3 and showing another form of side panel which may be used with the design.

FIG. 6 is a view in side elevation of the support stand for a television receiver or similar article similar to that shown in FIG. 3 and showing another form of side panel which may be used with the design.

The sides of the stands not shown are a mirror image of the sides shown.

I claim:

The ornamental design for a support stand for a television receiver or similar article, substantially as shown and described.
